UNITED STATES PATENT OFFICE.

ALVIN EVANS KEPHART, OF EBENSBURG, PENNSYLVANIA.

AUTOMOBILE HORN.

Application filed March 27, 1925. Serial No. 18,660.

To all whom it may concern:

Be it known that I, ALVIN EVANS KEPHART, a citizen of the United States, residing at Ebensburg, in the county of Cambria and State of Pennsylvania, have invented a certain new and useful Automobile Horn, of which the following is a specification.

This invention, generally stated, relates to automobile horns, and has more especial relation to automobile horns actuated by the exhaust from the internal combustion or from a source of compressed gas or air calculated to be operated through the instrumentality of a hand pressed bulb and rubber tube connection.

The leading object of the present invention is to provide a simple, efficient, and comparatively inexpensive horn of the character stated in which an oscillatory is employed which may be maintained in a constant state of oscillation during supply of the source of actuating force.

A further object of the present invention resides in the provision of general details of construction and arrangement and combination of parts for attaining the results sought by the leading object. Other and further objects not at this time more specifically referred to will be hereinafter described.

The invention consists of the novel construction hereinafter described and finally claimed.

The nature, characteristic features and scope of the invention will be more fully understood from the following description taken in connection with the accompanying drawings forming part hereof, and in which:

Fig. 1, is a view in side elevation, partly sectioned, illustrating more or less diagrammatically an automobile horn as connected to the exhaust pipe of an internal combustion engine.

Fig. 2, is a view in cross section taken upon the line 2—2 of Fig. 1.

Fig. 3, is a fragmentary view in section taken upon the line 3—3 of Fig. 1.

Fig. 4, is a fragmentary view in central section illustrating a somewhat modified form of the invention.

Fig. 5, is a view in section taken upon the line 5—5 of Fig. 4.

Fig. 6, is a fragmentary view in section illustrating a further modified form of the invention; and

Fig. 7, is a view in section taken upon the line 7—7 of Fig. 6.

For the purpose of illustrating my invention I have shown in the accompanying drawings several forms thereof which are at present preferred by me, since the same have been found in practice to give satisfactory and reliable results, although it is to be understood that the various instrumentalities of which my invention consists can be variously arranged and organized and that my invention is not limited to the precise arrangement and organization of the instrumentalities as herein shown and described.

Referring to the drawings in detail the reference numeral 1 designates an automobile horn which is horizontally arranged and the neck 2 of which terminates in a substantially spherical shaped portion comprised of detachably arranged sections 3 and 4. Referring now more particularly to Figs. 1 to 3 inclusive, there is shown as being clamped as at 5 between the sections 3 and 4 a fixed plate 6. Fixed to plate 6 in any appropriate manner is the flange 7 of a horizontally arranged pipe 8 which pipe is projected through the section 4 and is connected by a union 9 with a pipe 10. The fixed plate 6 is apertured as at 31 in alignment with the said pipe 8. The pipe 10 is coupled to a valve 11 interposed in the pipe section 12 leading from the exhaust of an internal combustion engine (not shown). Secured with respect to plate 6 so as to be afforded an oscillatory movement with respect thereto is a disc 13. In practice the disc 13 is secured to plate 6 by means of bolts 14 provided with sleeves 15 fitted over said bolts so that the apertured portion 16 of the disc 13 may have longitudinal movement over said sleeves. The disc 13 may be made of metal or any other suitable material calculated to give an audible sound when the exhaust from the internal combustion engine is permitted to pass through pipes 10 and 8, for impinging against said disc. Obviously, instead of having the pipe 10 connected with the in-

ternal combustion of an engine said pipe 10 may be connected to a source of compressed gas or air. The valve 11 may be operated from the driver's seat by means of a pull chain 17. If compressed gas or air is the source of supply desired, obviously a bulb for hand compression and a rubber tube may be substituted for the valved connection. At such times as the operator of the automobile, motor boat, or the like, desires to operate the above described horn, valve 11 is open to permit the engine exhaust to pass through pipes 10 and 8 for impinging against disc 13. Since the pressure passing between the plate 6 and disc 13 moves at such velocity that the pressure is less than the atmospheric pressure upon the horn side of the disc 13 the oscillatory plate is moved toward the fixed plate 6 only to be moved away again by the impinging exhaust. Thus as the oscillatory plate 13 is free to move in opposite directions and since pressure may be exerted upon opposite sides thereof it is apparent that the oscillatory disc may be maintained in a constant state of oscillation at desired intervals. Referring now more especially to Figs. 4 and 5 the fixed plate 6 is the same as that shown in Figs. 1 to 3 inclusive but an additional fixed plate 18 is provided interposed between which fixed plates 6 and 18 is the oscillatory plate 19 which is centrally apertured as at 20. The plate 18 is fixed to plate 6 by means of bolts 21, sleeves 22 being provided to maintain plate 18 in spaced relation from plate 6 and the apertured portions of the disc 19 permit disc 19 to move toward and away from plates 6 and 18. Otherwise the construction is the same as above recited and the operation is the same. Referring to Figs. 6 and 7, a pair of fixed discs designated 23 and 24 respectively are provided, said discs being secured to the sections 3 and 4 by means of braces 25 and 26. Between these fixed plates 23 and 24 is arranged an oscillatory plate 27 centrally apertured as at 28, bolts 29 and sleeves 30 being provided as in the foregoing figures to permit oscillatory movement of disc 27 with respect to plates 23 and 24. It will now be apparent that I have devised a novel and useful construction which embodies the features of advantage enumerated as desirable in the statement of the invention and the above description and while I have in the present instance shown and described the preferred embodiments thereof which have been found in practice to give satisfactory and reliable results, it is to be understood that the same are susceptible of modification in various particulars without departing from the spirit or

scope of the invention or sacrificing any of its advantages.

What I claim is:

1. In a device of the character stated the combination of a horn, a closed compartment in communication with said horn, a fixed plate arranged within said compartment, an oscillatory disc arranged for movement toward and away from said fixed plate and normally displaceable under the influence of atmosphere pressure, and a pipe for the admission of atmospheric pressure extended through the rear wall of said casing horizontally into said compartment, said pipe being rigidly connected with the fixed plate for conveying a medium under pressure for displacing said oscillatory disc. 65 70 75

2. In a device of the character stated the combination of a horn, a closed compartment in communication with said horn, a fixed plate arranged within said compartment, an oscillatory disc arranged for movement toward and away from said fixed plate and normally displaceable under the influence of atmospheric pressure, bolts provided with sleeves carried by the fixed plate and upon which sleeves said oscillatory plate is movable, and a pipe extending into the said compartment and connected with the fixed plate for conveying a medium under pressure for displacing said oscillatory disc. 80 85 90 95

3. In a device of the character stated the combination of a horn, a closed compartment in communication with said horn, said compartment being comprised of a pair of substantially hemispherical shells clamped together, a fixed plate arranged within said compartment, an oscillatory disc arranged for movement toward and away from said fixed plate and normally displaceable under the influence of atmospheric pressure, and a pipe extending into said compartment and connected with the fixed plate for conveying a medium under pressure for displacing said oscillatory disc. 100 105 110

4. In a device of the character stated the combination of a horn, a closed compartment in connection with said horn, a fixed plate within said compartment, an oscillatory disc arranged for movement toward and away from said plate, an internal-combustion engine exhaust, a pipe extending from said exhaust pipe through said compartment and connected to the fixed plate which plate is apertured in connection with said pipe, and manually operable means for regulating the supply of pressure from said exhaust to said compartment. 115 120

In testimony whereof, I have hereunto signed my name.

ALVIN EVANS KEPHART.
